UNITED STATES PATENT OFFICE

2,113,219

MICROPHONE

Harry F. Olson, Collingswood, and Frank Massa,
Oaklyn, N. J., assignors to Radio Corporation
of America, a corporation of Delaware

Application May 31, 1934, Serial No. 728,202

3 Claims. (Cl. 179—115.5)

This invention relates to velocity microphones, and concerns particularly a velocity microphone having a cosine directional characteristic within a predetermined frequency range.

5 One object of the invention is to provide such a microphone which will avoid the pick-up of reverberated sounds.

Another object of the invention is to provide a microphone of the type referred to which is 10 capable of being manufactured to any desired frequency-directional characteristics.

Another object of the invention is to provide an improved type of velocity or "ribbon" microphone.

15 In the drawings:

Figure 1 shows our improved microphone with the cover removed therefrom.

Figure 2 is an elevation of the pole-pieces and ribbons thereof.

20 Figure 3 is a top view of the pole-pieces and ribbons with the ribbon clamps and conductors removed.

Figure 4 is a plot of the response of our microphone.

25 The directional characteristics of the velocity ribbon microphone are independent of the frequency. In certain types of sound motion picture sets the reverberation time is greater at the higher frequencies. Furthermore, it is also desirable in some recordings to increase the discrimination against reflected sound to obtain a more intimate effect. To accomplish these objectives requires a sharpening of the directional characteristics of the velocity microphone at the 30 higher frequencies. It is the purpose of this invention to provide a velocity microphone employing two ribbons separated in space and which exhibits a cosine directional characteristic in the range below 1000 cycles and a progressively 35 sharper characteristic above 1000 cycles.

40 The directional characteristic of the conventional velocity ribbon microphone is given by

$$e = e_0 \cos \theta$$

45 where

e =voltage output of the microphone for the angle θ

e_0 =output of the microphone for $\theta=0$

50 θ =angle between the normal to the ribbon and the line joining the sound source and the ribbon.

Let us consider a velocity microphone equipped with two parallel ribbons separated by a distance 55 D. The voltage output for a source of sound in

the plane passing through the ribbons and normal to axis of the ribbons is given by

$$e = e_0 \cos \theta \cos \left(\frac{\pi D \sin \theta}{\lambda} \right)$$

where

θ =angle between the normal to the ribbons and the line joining the sound source and the center line of the two ribbons,

D=distance between the ribbons,

$$\lambda=\text{wavelength}=\frac{c}{f}$$

c=velocity of sound, and

f=frequency

15 The theoretical directional characteristics are shown in Fig. 4. The observed directional characteristics are also shown in Fig. 4.

20 The essential details of construction are shown in Figs. 1, 2 and 3. Two corrugated aluminum ribbons .0001" thick (similar to the ribbons used in the usual velocity microphone) are separated by a distance of 2 inches between centers as shown in these figures. The magnetic structure is designed to replace the pole assembly in the usual 25 velocity microphone.

20 The two ribbons are electrically connected, as shown in Fig. 2, in order that the effective inductance of the ribbon circuit will be reduced to a minimum and electrical pick-up thereby prevented.

30 The general construction and operation of the usual velocity microphone referred to above is shown, described and claimed in the patent to Olson No. 1,885,001 issued October 25, 1932 and, except for the arrangement of pole-pieces and 35 ribbons, the present device is constructed in the same manner.

35 To describe in more detail herein the construction of our microphone:

40 A permanent magnet 10 is mounted upon an appropriate casing 11 which houses an appropriate transformer, as described in the said prior patent. Upon the poles of the magnet 10 are mounted pole-pieces 12 and 13 of appropriate 45 high-permeability iron which are so shaped as to provide a uniform and high magnetic flux across the ribbons 14 and 15 which are constructed in accordance with the said prior patent.

45 Between the said ribbons is interposed a pole-piece yoke generally indicated at 16 and comprising the secondary pole-pieces 17 and 18 and the magnetic connecting members 19 and 20, distributing and concentrating the magnetic flux 50 equally between the two ribbons.

5 The ribbons are supported by, and connected to, the clamps 21, 22, 23 and 24, which are respectively insulated from the rest of the structure by the insulating members, preferably of Bakelite, hard rubber, or the like, 25, 26, 27 and 28.

10 The several leads 30, 31 and 32 are connected as illustrated in Fig. 2, so that the ribbons are connected in series but not in opposition.

15 10 This double ribbon microphone as shown in Fig. 1 has shown a measured flux density of 1450 gausses in each air gap. This is somewhat higher than half the flux density in a corresponding velocity microphone with a single air gap. The 15 increased magnetic efficiency results from the reduction in pole face leakage.

20 Frequency response measurements made along the axis passing between the ribbons and normal to the plane of the ribbons in this microphone show the same characteristic as obtained with a standard velocity microphone. The observed directional characteristics of the microphone at various frequencies are shown on the right hand portion of Fig. 4. On the left hand portion of 25 the same figure are shown the theoretical directional characteristics which check fairly well with the observed curves.

25 As described in the said prior patent, the dimensions of the several pole-pieces determine the 30 individual frequency characteristics of the individual ribbons. However, in the present device, the cosine frequency directional characteristic referred to is determined by the lateral spacing between the ribbons.

35 35 We do not mean to be limited in the present invention to the specific construction, characteristics, and dimensions described above as the pres-

ent preferred and commercial form of our invention, as it will be apparent that within the scope of our invention we may provide any number of ribbons in a corresponding arrangement; or we may render the individual frequency characteristics of the ribbons asymmetrical by altering the size of the baffles around them so as to make the curves of Fig. 4 "lop-sided"; or we may place the ribbons at a different angle to each other to modify the frequency-directional characteristics. 5 10

Having now described our invention, we claim:

1. A unitary device of the class described comprising a plurality of physically independent, series connected acoustically velocity-controlled 15 elements located at a predetermined distance from each other within the unit, and magnetic means common to both of said elements for supplying a magnetic field for each of them.

2. A microphone comprising a magnet, parallel 20 pole-pieces mounted on said magnet, an intermediate pole-piece between said parallel pole-pieces, and separately-supported, parallel approximately linear acoustically velocity-controlled 25 elements mounted between each of said parallel pole-pieces and said intermediate pole-piece.

3. A microphone comprising a magnet, parallel pole-pieces mounted on said magnet, an intermediate pole-piece between said parallel pole-pieces, and separately-supported, parallel approximately linear acoustically velocity-controlled 30 elements mounted between each of said parallel pole-pieces and said intermediate pole-piece and in the same plane.
